UNITED STATES PATENT OFFICE.

SAMUEL D. REYNOLDS, OF ROCHELLE, ILLINOIS.

ROAD-WAGON.

SPECIFICATION forming part of Letters Patent No. 269,112, dated December 12, 1882.

Application filed September 16, 1882. (No model.)

To all whom it may concern:

Be it known that I, SAM'L. D. REYNOLDS, of Rochelle, in the county of Ogle and State of Illinois, have invented certain new and useful 5 Improvements in Road - Wagons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to improvements in road-wagons; and it consists in certain details 15 of construction and combinations of parts, as will be more fully explained, and pointed out in the claims.

In the drawings, Figure 1 is a side view of my improvement. Fig. 2 is a rear end view, 20 and Fig. 3 is a detached view of the front axle and spindle and rear spindle and plates.

A represents the body of the wagon; B, the bottom thereof; and C, the end-gate, removably secured in position by two rods, D.

25 L are the rear spindles, formed integral with the metallic spindle-plates M. These spindles are of ordinary construction, and are strengthened at their bases or at the points of junction with the plates M by the ribs or webs d. The 30 plates M can be made of any desired shape, and are secured to the side cleats, N, of the wagon-body by suitable bolts and nuts. These spindles are situated considerably above the bottom of the wagon, and the plates thereof 35 are connected together by the flat metallic brace P, which latter bears against and is secured to the transverse bar O, rigidly secured to the bottom of the wagon. The ends of this flat metallic brace are then curved upward and 40 removably secured to the plates M by the lower bolt, e, which latter extends from one side of the wagon to the other, and assists in securing both plates M in position, and also assists in bracing the wagon. The front drop-axle, Q, is 45 made of wood, and is secured to the wagon-body by a suitable king-bolt, N. This axle is considerably wider than the ordinary axle, and is provided at opposite ends with the angular plates R, having the spindles S formed integral therewith. These plates are each pro-

vided with a horizontal portion, i, adapted to form seats or rests for the opposite extremities of the flat wooden axle, to which they are secured by screw-bolts and nuts. The vertical and horizontal portions of each of these plates 55 are connected together and strengthened by one or more ribs or webs, f.

The wagon-hound T is secured to the under-side of the wooden axle, while this whole structure just described is strengthened by the flat 60 metallic truss or brace U. This truss passes under the hound T, and the ends thereof incline or curve upward, and are rigidly secured to the lower faces of the horizontal portions of the spindle-plates. The front end of the reach-bar V rests between the truss U and the axle, and receives the lower end of the king-bolt. The spindles are screw-threaded on the ends 65 for the retention of the holding-nuts. By placing the body of the wagon low down between 70 the wheels and bracing the parts, as described, a strong and durable road-vehicle is formed, which is particularly adapted for heavy work, while at the same time lighter material can be employed in construction, which materially 75 lessens the cost of manufacture. The peculiar structure employed for securing the rear wheels in position also prevents the bottom of the wagon from sagging and the sides from separating during the transportation of heavy 80 loads.

It is evident that slight changes in the construction and relative arrangement of the different parts might be resorted to without departing from the spirit and scope of my invention, and hence I would have it understood 85 that I do not limit myself to the exact construction shown and described, but consider myself at liberty to make such changes and alterations as come within the spirit and scope 90 of my invention.

I do not claim in this application the improved construction of wagon-body and end-gate, but reserve to myself the right to file a separate application for such improvements. 95

What I claim is—

1. The combination, with the rear spindles and plates, the latter being secured to the sides of the wagon-body, of a metallic brace passing transversely under the bottom of the wagon- 100

body and rigidly secured at its opposite extremities to the spindle-plates.

2. The combination, with the rear spindles and spindle-plates, the latter being secured to the sides of the wagon-body, of the transverse bar O, and a flat metallic brace secured to the lower face of the transverse bar, and secured at its opposite ends to the spindle-plates, substantially as set forth.

10 3. The combination, with the rear spindles and spindle-plates, the latter being secured to the side cleats, N, of the wagon-body, of the transverse bar O, brace P, and bolt e, all of the above parts combined and adapted to operate as described.

15 4. The combination, with the front spindles and angular spindle-plates, the latter being braced, as shown, of the front axle, the opposite ends of which are secured to the upper faces of the horizontal portions of the spindle-plates, and the flat metallic truss passing below said axle, and rigidly secured at its outer

ends to the lower faces of the said horizontal portions of the spindle-plates, substantially as set forth.

25 5. The combination, with a wagon-body and king-bolt, of the front spindles and spindle-plates, the wooden axle, and truss, all of the above parts combined and adapted to operate as described.

30 6. The combination, with the front spindles and spindle-plates, the flat wooden axle, the wagon-hound, and reach-bar, of the flat metallic truss passing below said hound, and secured at its opposite ends to the spindle-plate, all of the above parts combined and adapted to operate as described.

In testimony that I claim the foregoing I have hereunto set my hand this 31st day of August, 1882.

SAMUEL DAVIS REYNOLDS.
